UNITED STATES PATENT OFFICE.

WALTER B. FOGH, OF SEATTLE, WASHINGTON.

PROCESS OF REMOVING SOLID OILS FROM CANS.

Specification of Letters Patent. Patented Aug. 24, 1920.

1,350,599.

Application filed November 6, 1918. Serial No. 261,434.

To all whom it may concern:

Be it known that I, WALTER B. FOGH, a citizen of the United States, and resident of the city of Seattle, county of King, and State 5 of Washington, have invented certain new and useful Improvements in Processes for Removing Solid Oils from Cans, of which the following is a specification.

My invention consists of an improved 10 process or method of removing materials which are in a solid or semisolid condition at normal temperatures, from containers. To readily transfer materials of this sort from containers to storage tanks or other 15 large containers, it is necessary to first liquefy the same by the application of heat.

The object of my invention is to more rapidly secure this liquefaction of the product and thereby to more quickly put it in 20 condition such that it may be transferred by the use of pipes or troughs from one set of containers to another.

The particular steps which constitute my 25 process will be herein described and then defined by the claim.

In the accompanying drawings I have 30 illustrated an apparatus intended for this purpose.

Figure 1 shows a longitudinal section 35 through an apparatus intended for this purpose.

Fig. 2 is a transverse section through the 40 same.

Fig. 3 is a view, showing more in detail, 45 the manner of supporting the small containers and of applying my process to the liquefaction and removal of the contents thereof.

Considerable quantities of products such 50 as described, are shipped in cans from abroad and upon receipt in this country, are removed from these small cans into storage tanks or tankcars, for transportation to points of final use. Such products, of which cocoanut oil is a good illustration, are solid 55 or semisolid at any ordinary temperatures. The melting and removal of this oil by my process is secured by first heating a portion of such oil until it is in a fluid condition and then discharging this oil in small jets into 60 the semisolid or solid mass of the oil in the containers, from which it is desired to remove it.

It is well known that a liquid jet dis- 65 charged violently upon any congealed mass, will cause the same to melt much more rapidly than may be done by exposing the same

to contact with either hot air or hot liquid. The rapid flow of the liquid over the surface of the congealed mass causes a more rapid transfer of heat between the liquid and the 60 congealed mass and therefore causes a more rapid melting of the latter.

In applying my invention to a product under the conditions named, namely, wherein it is contained within tin cans or like containers, I prefer, as a first or preparatory step, to remove one head end of the can, at least to such an extent as to expose as large a portion of the end surface of the mass as possible. The can 4 illustrated in the drawing is supposed to be a can such as the five-gallon can which is very widely employed for shipment of kerosene oil. These cans, as illustrated, are supposed to have one head end removed.

They are then placed upon supporting bars, as 1, which are preferably placed toward the side edges of the head of the can, so as to leave the main body of the can end exposed. To hold this more securely in 80 shape, guide bars 10 have been shown. These cans 4 are placed in a chute of this sort and passed through a melting chamber 2, which chamber consists of a tank which either incloses the entire apparatus, or a 85 tank 3, which is placed beneath the chutes so as to catch oil as it melts.

The oil may be supplied for discharge upon the ends of these cans through a pipe 7, which pipe has a series of holes in its 90 upper side adapted to discharge a spray of oil into the cans. The cans may be moved through the chute by any suitable means, as for instance, by an endless conveyer 6, having disk-like plates 60 secured thereto and passing over wheels 61 at each end. The tank 3 and its contents may be heated by any suitable means. I have illustrated a furnace 95 5 beneath the same, although steam pipes may be employed whenever desired.

The oil may be drawn from the tank 3 and discharged to the pipe 7 by means of a pump, as 8, which discharges through a pipe 80 to a header 70, which header connects as many of the spray pipes 7 as may be employed.

In this manner a number of jets of the heated oils are discharged against the exposed end surface of the mass contained in the containers 4. This rapidly melts the oil, 110 and as the cans are first placed in position such that they would drain by gravity, they

are promptly discharged into the tank 3 from which it may be drawn and discharged through pipes to any point desired.

I have found that this method of treating 5 the oil for melting it, secures a much more rapid melting of the oil than can be secured by any other plan. It therefore reduces very materially the cost of the apparatus for melting the oil, reduces the space required 10 for the same, and the time for doing the work.

What I claim as my invention is:

The process of removing solid and semi-solid oils from cans which consists in first 15 opening the cans and placing them in position to drain by gravity, and then discharging melted portions of the same oil into the open ends of the cans.

Signed at Seattle, Washington, this 24th day of October, 1918.

WALTER B. FOGH.
